UNITED STATES PATENT OFFICE.

WILLIAM EARL McLAUGHLIN, OF MIDDLETOWN, OHIO.

LAMP-LOCK.

1,125,143.

Specification of Letters Patent.

Patented Jan. 19, 1915.

Application filed February 7, 1914. Serial No. 317,194.

To all whom it may concern:

Be it known that I, WILLIAM EARL McLAUGHLIN, a citizen of the United States, residing at Middletown, Butler county, Ohio, have invented certain new and useful 5 Improvements in Lamp-Locks, of which the following is a specification.

This invention relates to improvements in devices for locking incandescent electric 10 lamps in their sockets so as to prevent unauthorized removal of the lamps. Lamp locks have been arranged to be operated by a key, but these locks fail in the hands of a pilferer having a key or other tool by means 15 of which he may open the lock. Lamp locks have also been so arranged that the lamp could not be removed from its socket except by breaking the lamp, thus rendering the lamp useless to a pilferer, but this system was undesirable for the owner. My improved lamp lock is keyless and is, in a 20 measure, on the order of the combination safe lock, in that a lamp can be removed from its socket only by one who understands the trick of the thing.

My invention may be applied to a variety of lamp sockets and in a variety of forms but I have seen fit to set forth my invention as embodied in a particular lamp 25 socket of known form.

My invention will be readily understood from the following description taken in connection with the accompanying drawing in which:—

Figure 1 is a vertical diametrical section of a lamp socket embodying my invention, the section being taken in the plane of line *b* of Figs. 2 and 3: Fig. 2 a plan of the upper porcelain disk: Fig. 3 a plan of the lower porcelain disk: Fig. 4 a plan of the top disk of the socket proper: Fig. 5 a vertical section of the spring pawl in the plane of line *b* of Fig. 3; and Fig. 6 a panoramic section of the top-disk of the socket proper 45 taken on the circular line *c* of Fig. 4, the ends of this panoramic section being indicated by the line *d* and the direction of view being indicated by the arrow *e* of Fig. 4.

In the drawing:—1, indicates the socket proper which is threaded, and into which the threaded shank of the lamp is to be screwed: 2, a lower fixed porcelain disk disposed concentrically over the socket: 3, an upper fixed porcelain disk disposed above 55 the lower porcelain disk: 4, bolts securing the two porcelain disks together: 5, the top

disk of the socket proper, this disk being of insulating material and fixedly secured to the top of the socket proper; 6, screws securing the socket proper to disk 5 and serving also to secure to both these parts a metallic ring to be hereinafter referred to: 7, the central contact spring for the central teat of the lamp, this spring being secured to disk 5: 8, a central bolt securing disk 5, 60 spring 7 and the two porcelain disks and their accessories together but permitting the socket proper with the accessories carried by it to rotate independent of the united porcelain disks: 9, a metallic strap in electrical 65 connection with central bolt 8, this strap being above lower porcelain disk 2: 10, a second metallic strap: 11, binding screws for the two incoming wires which are to supply current to the lamp: 12, a hollow 70 metallic plug connected to the inner end of strap 10 and extending down through lower porcelain disk 2: 13, a spring plunger or pawl projecting from the lower end of plug 12: 14, the outer shell of the general socket: 15, the dome of the general socket: 16, the 75 threaded opening in the dome by means of which the general socket may be attached to a fixture: 17, insulating linings for the shell and dome: and 18, a metallic ring secured, 80 by screws 6, to insulating disk 5 and having its upper surface engaged by the lower end of spring plunger 13 regardless of the angular position of socket proper 1, relative to the other parts of the device. All of the 85 parts thus far specifically referred to go to make up a lamp socket of rather well known construction in which, by reason of the socket proper being capable of freely rotating to the left, or left-hand screw-wise, the 90 shank of the lamp cannot be unscrewed from the socket. The current from one of the incoming wires will go to spring 7 and thence to the central teat of the lamp, while the current from the other incoming wire will 95 go through the spring plunger and ring 18 and screws 6 to the socket proper and thence to the threaded metallic collar of the shank of the lamp, as usual. As thus far described 100 it is manifest that a lamp once screwed into the socket could not be unscrewed therefrom owing to the fact that the socket proper is free to turn with the lamp. But it is equally manifest that a lamp could not be satisfactorily screwed into the socket, owing to the 105 freedom with which the socket proper may turn.

In proceeding I will use the expression "to the right" or "right" as indicating that direction of motion involved in screwing the lamp into a socket and I will use the expression "to the left" or "left" as indicating that direction of motion involved in unscrewing a lamp from a socket.

- Proceeding with the drawing: 19, indicates a radial shoulder upon the upper surface of ring 18, this shoulder facing to the right, or in such direction as to come against spring plunger 13 when the socket proper turns to the right: 20, a second similar radial shoulder on the ring: 21, a third similar radial shoulder on the ring, this third shoulder, however, being an insulating insert in the ring instead of in the metal of the ring itself: 22, a segmental insert of insulating material secured to disk 5 to form a circumferential continuation of ring 18: 23, a radial shoulder on ring 18, but facing to the left, or in such direction as to come against spring plunger 13 when the socket proper rotates to the left: 24, a segmental ball-race 25 in ring 18, between shoulders 20 and 23: 25, a ball adapted to roll freely in this segmental slot and of such size that its upper surface will project at least as high as shoulder 23: 26, a second ball in the segmental slot: and 27, the inclined upper surfaces of ring 18 leading from the foot of one of the rightwardly presenting shoulders to the top of the succeeding shoulder.
- The plunger 13 should be prevented, by some means, from descending into ball-race 24, which prevention in the present case is effected by having the plunger of a diameter somewhat in excess of the width of the ball-race.
- 40 If the shank of a lamp be started to screw into the socket proper, the latter, being free to turn, will most likely turn with the shank but very quickly will be arrested by one of the shoulders 19, 20, or 21, coming in contact with spring plunger 13 whereupon the lamp may be screwed home. Assuming, now, that an attempt be made to unscrew the lamp from the socket, if spring plunger 13 happens to be engaging one of the inclined surfaces 27, the turning of the lamp to the left will cause the socket proper to turn to the left, the spring plunger simply riding up on the inclined surfaces after the manner of a pawl on the rear of a ratchet tooth.
- 50 If the spring plunger happens to be on that portion of the ring carrying the balls, as the plunger is illustrated in full lines in Fig. 6, the plunger will ride up on the balls and over shoulder 19, precisely as it rode up on the inclined surfaces. In other words, owing to the ratchet character of the construction, the lamp could be turned to the left indefinitely without unscrewing from its socket, for the socket would turn with it.
- 65 The only way to lock the socket proper

against rotation, so that the lamp can be unscrewed, is to have the leftward shoulder 23 come into engagement with the spring plunger 13, and the trick is to accomplish this engagement. Ignore, for the present, second ball 26, and assume that ball 25 only is present. By rotating the lamp, and with it the socket proper to the left, the spring plunger will eventually reach ball 25, and this fact will be known, to the initiated, by the feel of the thing. The spring plunger, riding up on the ball, will reach the position indicated by the plunger in dotted lines in Fig. 6. It must go past the ball and the leftward turning of the lamp must cease. Now, by turning the lamp to the right, the ring 18 turns with it, of course, and ball 25, coming against the plunger, becomes pushed to the left if it has not already moved to the left, and the spring plunger goes down to the left of shoulder 23. The ring and the socket proper are now locked against leftward turning and the lamp may be readily unscrewed from the socket. The second ball 26 has little to do with the operation, except to embarrass and hinder one who may think he is wise, for, feeling ball 26, he may go through the above described backward operation, which will do him no good at all, for ball 25 is the one to be dealt with.

Shoulder 19 to permit the screwing in of the lamp, and shoulder 23 to permit the unscrewing of the lamp, are all of the shoulders needed, shoulders 20 and 21 serving simply to add to the complexity of the trifling little shocks that may be felt in attempting to unscrew the lamp, and there may be as many of these non-essential shoulders as is judged best.

Insulating patch 22 in the ring on which the spring plunger bears is not essential but it serves a good office in some cases. In the idle attempt to unscrew the lamp, as has been explained, ring 18 turns with it and each time the spring plunger reaches insulating patch 22 the current to the lamp is cut off and is reestablished when the metallic portion of the ring gets under the spring plunger. This scheme serves as a switch by means of which the lamp may be cut out of circuit by rotating it without unscrewing it a particle from its socket, but in some cases it serves, by the flashing of the lamp, as indicating that an attempt is being made to unscrew the lamp.

In the incandescent electric lamp art the term "socket" is applied to the general structure attached to the fixture to serve in receiving the lamp, and in the present case that term would be applied to the entire structure set forth. In the present case I have referred to the direct lamp-receiving feature as the socket proper, to distinguish it from the structure as a whole. In the present case the socket proper is rotatable

relative to the fixed parts represented by the porcelain disks 2 and 3, and in the claims I will employ the term "head" as comprehending fixed disk 2 relative to which the socket proper rotates.

It is to be understood that the particular construction set forth is merely a single exemplification of my invention, which invention will lend itself to a variety of embodiments. I have sought merely to explain the principle of my invention and the best form in which I at present contemplate embodying it.

I claim:

1. A lamp-lock comprising, a head, a socket proper secured to the head and rotatable relative thereto, a first shoulder carried by the socket proper and presenting itself to the right, a second shoulder carried by the socket proper and presenting itself to the left, a spring pawl supported by the head and adapted to convey current to the socket proper and to engage the first shoulder and arrest the turning of the socket proper to the right and to engage the second shoulder and arrest the turning of the socket proper to the left, and a movable lifting device carried by the socket proper at the left of the second shoulder and adapted to raise said pawl to the top of the second shoulder as the socket proper is turned to the left and to retreat to inactive position so as to permit the pawl to descend to the left of the second shoulder when the socket proper is turned to the right from position corresponding with the raised position of the pawl, combined substantially as set forth.

2. A lamp-lock comprising, a head, a socket proper secured to the head and rotatable relative thereto, a first shoulder carried by the socket proper and presenting itself to the right, a second shoulder carried by the socket proper and presenting itself to the left, a spring pawl supported by the head and adapted to convey current to the socket proper and to engage the first shoulder and arrest the turning of the socket proper to the right and to engage the second shoulder and arrest the turning of the socket proper to the left, a movable lifting device carried by the socket proper at the left of the second shoulder and adapted to raise said pawl to the top of the second shoulder as the socket proper is turned to the left and to retreat to inactive position so as to permit the pawl to descend to the left of the second shoulder when the socket proper is turned to the right from position corresponding with the raised position of the pawl, and a second movable lifting device carried by the socket proper at the left of the first lifting device, combined substantially as set forth.

3. A lamp-lock comprising, a head, a

socket proper secured to the head and rotatable relative thereto, a first shoulder carried by the socket proper and presenting itself to the right, a second shoulder carried by the socket proper and presenting itself to the left, a spring pawl supported by the head and adapted to convey current to the socket proper and to engage the first shoulder and arrest the turning of the socket proper to the right and to engage the second shoulder and arrest the turning of the socket proper to the left, and a rolling lifting device carried by the socket proper at the left of the second shoulder and adapted to have said pawl ride up it to the top of the second shoulder as the socket proper is turned to the left and to be rolled back to inactive position so as to permit the pawl to descend to the left of the second shoulder when the socket proper is turned to the right from position corresponding with the raised position of the pawl, combined substantially as set forth.

4. A lamp-lock comprising, a head, a socket proper secured to the head and rotatable relative thereto, a first shoulder carried by the socket proper and presenting itself to the right, a second shoulder carried by the socket proper and presenting itself to the left, a spring pawl supported by the head and adapted to convey current to the socket proper and to engage the first shoulder and arrest the turning of the socket proper to the right and to engage the second shoulder and arrest the turning of the socket proper to the left, a rolling lifting device carried by the socket proper at the left of the second shoulder and adapted to have said pawl ride up it to the top of the second shoulder as the socket proper is turned to the left and to be rolled back to inactive position so as to permit the pawl to descend to the left of the second shoulder when the socket proper is turned to the right from position corresponding with the raised position of the pawl, combined substantially as set forth.

5. A lamp-lock comprising, a head, a socket proper secured to the head and rotatable relative thereto, a first shoulder carried by the socket proper and presenting itself to the right, a second shoulder carried by the socket proper and presenting itself to the left, a spring pawl supported by the head and adapted to convey current to the socket proper and to engage the first shoulder and arrest the turning of the socket proper to the right and to engage the second shoulder and arrest the turning of the socket proper to the left, a ball-race carried by the socket proper, and a ball rolling in said ball-race at the left of the second shoulder and adapted to have said pawl ride up

it to the top of the second shoulder as the socket proper is turned to the left and to be rolled back to inactive position so as to permit the pawl to descend to the left of the 5 second shoulder when the socket proper is turned to the right from position corresponding with the raised position of the pawl, combined substantially as set forth.

6. A lamp-socket comprising, a head, a 10 socket proper secured to the head and rotatable relative thereto, a first shoulder carried by the socket proper and presenting itself to the right, a second shoulder carried by the socket proper and presenting itself to 15 the left, a spring pawl supported by the head and adapted to convey current to the socket proper and to engage the first shoulder and arrest the turning of the socket proper to the right and to engage the second 20 shoulder and arrest the turning of the socket proper to the left, a ball-race carried by the socket proper, a ball rolling in said ball-race at the left of the second shoulder and adapted to have said pawl ride up it to the top of the 25 second shoulder as the socket proper is turned to the left and to be rolled back to inactive position so as to permit the pawl to descend to the left of the second shoulder when the socket proper is turned to the 30 right from position corresponding with the raised position of the pawl, and a second ball carried by the socket proper at the left of the first ball, combined substantially as set forth.
- 35 7. A lamp-lock comprising, a head, a socket proper secured to the head and rotatable relative thereto, a first shoulder carried by the socket proper and presenting itself to the right, additional shoulders carried by the socket proper and presenting 40 themselves to the right, a second shoulder carried by the socket proper and presenting itself to the left, a spring pawl supported by the head and adapted to convey current 45 to the socket proper and to engage either

the first shoulder or the additional shoulders and arrest the turning of the socket proper to the right and to engage the second shoulder and arrest the turning of the socket proper to the left, and a movable lifting device carried by the socket proper at the left of the second shoulder and adapted to raise said pawl to the top of the second shoulder as the socket proper is turned to the left and to retreat to inactive position so as to permit the pawl to descend to the left of the second shoulder when the socket proper is turned to the right from position corresponding with the raised position of the pawl, combined substantially as set forth.

8. A lamp-lock comprising, a head, a socket proper secured to the head and rotatable relative thereto, a circumferentially interrupted ring carried by the socket proper, a first shoulder carried by the ring and presenting itself to the right, a second shoulder carried by the ring and presenting itself to the left, a spring pawl supported by the head and adapted to engage the ring and convey current to the socket proper and to engage the first shoulder and arrest the turning of the socket proper to the right and to engage the second shoulder and arrest the turning of the socket proper to the left, and a movable lifting device carried by the socket proper at the left of the second shoulder and adapted to raise said pawl to the top of the second shoulder as the socket proper is turned to the left and to retreat to inactive position so as to permit the pawl to descend to the left of the second shoulder when the socket proper is turned to the right from position corresponding with the raised position of the pawl, combined substantially as set forth.
